UNITED STATES PATENT OFFICE.

CHARLES ROEMER, OF JAMESTOWN, NEW YORK, ASSIGNOR TO THE PANDORA SIGN CORPORATION, OF JAMESTOWN, NEW YORK, A CORPORATION OF DELAWARE.

CHANGEABLE EXHIBITOR.

Application filed October 11, 1924. Serial No. 743,074.

To all whom it may concern:

Be it known that I, CHARLES ROEMER, a citizen of the United States, residing at Jamestown, in the county of Chautauqua and State of New York, have invented certain new and useful Improvements in Changeable Exhibitors, of which the following is a specification, reference being had to the accompanying drawings.

This invention relates to changeable exhibitors, and more particularly to a device of this character having an endless perforated belt passing between illuminating elements and a translucent plate upon which the perforations of the belt define letters or characters for shutting out the undesirable rays of light.

An important object of the invention is to provide a device of this character in which kinking and sagging of the perforated belt or tape bearing the message is prevented, and more particularly the provision of a carrier tape and apparatus for mounting and driving the same which supports and mounts this perforated belt or tape at all times in proper alignment.

A further object of the invention is to provide a device of this character in which the belt may be readily removed to permit changing thereof, and in which means are provided for giving a desired color to the lettering or characters produced.

A still further object of the invention is to provide a device of this character which is simple in its construction and operation, which may be readily and cheaply produced, and which will be durable and efficient in service.

These and other objects I attain by the construction shown in the accompanying drawings, wherein for the purpose of illustration is shown a preferred embodiment of my invention and wherein:

Figure 1 is a side elevation of a changeable exhibitor constructed in accordance with my invention;

Figure 2 is a plan view thereof;

Figure 3 is a vertical longitudinal section therethrough;

Figure 4 is a horizontal longitudinal section therethrough;

Figure 5 is a transverse section therethrough;

Figure 6 is an enlarged detail sectional

view through one of the adjustable mounting brackets;

Figure 7 is a perspective of one of the adjustable mounting brackets detached.

Referring now more particularly to the drawings, the numeral 10 indicates a base 60 from which extends upwardly a rectangular open top framework 11, the side walls of which, indicated at 12, are provided with openings 13 in which is arranged a translucent plate 14, these openings being of less 65 length than the sides for a purpose presently to appear. A cover 15 is provided having flanged edges 16 engaging downwardly over the sides to maintain the cover in position and at the same time to permit the same to 70 be readily lifted from the side walls to permit inspection, adjustment or interchanging of the parts located within the side walls upon the base, as hereinafter described. Arranged within the side walls upon the base 75 are a plurality of brackets 17, 18 and 19, the bracket 17 being an operating end bracket, the bracket 18 an intermediate bracket, and the bracket 19 an adjusting end bracket, and as such hereinafter referred to. These 80 brackets are each attached at their lower ends to the base, as indicated at 20, and each have approximately midway their height an opening 21, the bottom surface of which is 85 flat. Extending through the openings 21 is a support in the form of a flat bar 22 which is secured to each of the brackets at its point of engagement with the flat bottom thereof, as indicated at 23, thus rigidifying the brackets to one another at a point spaced 90 above the base. This support serves as a mounting for a plurality of illuminating elements 24, which in the present instance are shown as mounted upon opposite sides of the support intermediate the brackets 17, 18 95 and 19. It will be understood that the number of brackets 18 employed depends entirely upon the length of the sign casing and may be varied as is found necessary or desirable.

Each of the brackets is further provided at its upper end with a horizontally extending arm 25 forming a means for mounting above the bracket pulleys, the pulley of the bracket 17 being designated at 26, while those of the intermediate and adjusting end brackets are indicated at 27. The operating end bracket 17 is provided at that

face thereof next adjacent the adjacent end of the casing with a shelf 28 spaced from the base 10, this shelf being a support for a gear box 29 within which is contained reduction gearing, as generally indicated upon the drawings. Through the side wall of this casing extends a shaft 30, the end of which is provided with a large pulley 31. Beneath the shelf upon the base is mounted 10 a motor 32, the armature shaft of which has a drive pulley 33 connected with the pulley 31 by a belt 34. Through the upper wall of the gear box 29 extends a vertical shaft 35, the upper end of which is directed 15 through the arm 25 of the bracket 17 and has secured thereto the pulley 26, the lower end of the pulley hub 26^a resting upon the upper surface of the arm.

The arms 25 of the brackets 17 and 18 20 are each provided with a longitudinally extending slot, and these arms are preferably directed toward the opposite end of the casing from that at which the operating end bracket 17 is located. Within the slot of the arm 25 of the brackets 18 and 19 is slidably disposed a bolt 36, the head of which abuts the under surface of the arm and the shank of which is directed through the slot. Upon the upper surface of the arm a steel 30 sleeve 37 surrounds the bolt and is surrounded by a washer 38 and a lever nut 39. By tightening the lever nut, the sleeve may be held in adjusted positions longitudinally of the arm. Surrounding these sleeves are 35 the hubs 40 of the pulleys 27.

Each of the pulleys 26 and 27 is provided in its periphery with a V-shaped groove 41 for the reception of the inner face of a carrier belt 42 which conforms in shaping to 40 the groove so that it fits tightly therein. This belt may be tightened with relation to the pulleys by adjusting the pulley of the adjusting end bracket 19 to secure the desired tension of this carrier belt. The outer 45 surface of this belt is vertically disposed and has secured thereto a perforated tape or skirt 43, the perforations of which combine to produce any desired series of illustrations or message. It will be obvious that 50 the light from the illuminating elements passing through these perforations will be cast upon the translucent plate and will be readable therethrough, and that as the skirt is driven from the motor these perforations 55 will slowly pass the openings, permitting reading of the legend of the skirt. At each side of the casing, between the skirt and the illuminating element, is arranged a transparent tinting panel 44, the ends of which 60 are held in position by means of vertically disposed U-guides 45 extending upwardly from the base. It will be obvious that by changing these tinting panels any desired color or combination of colors in the characters finally produced may be had.

Since the device as hereinbefore described is capable of a considerable range of change and modification without materially departing from the spirit of my invention, I do not limit myself to such specific structure except as hereinafter claimed. 70

I claim:—

1. In a changeable exhibitor, a plurality of supports, a plurality of pulleys carried by the supports and arranged in a common plane and having their peripheries grooved, means for driving one of said pulleys, means for adjusting another of said pulleys toward and away from the first named pulley, an endless carrier belt having its inner face 75 conforming in shaping to the grooves of the pulleys and fitting into the grooves of all of said pulleys, a perforated skirt secured to the outer face of said carrier belt and freely depending therefrom, said pulleys 80 being of greater diameter than the width of any portions of said supports arranged between the opposed portions of the skirt whereby said skirt is free from engagement with said supports. 85

2. In a changeable exhibitor, a casing having a translucent panel in the longitudinal wall thereof, the casing including a base, a plurality of brackets spaced longitudinally of said base and extending upwardly therefrom, said brackets being secured at their lower ends to the base and having aligned openings formed therein at points spaced vertically from the base, a bar extending through said openings and secured to each of said brackets, illuminating elements carried by said bar, and means supported from the brackets limiting passage of the rays from the illuminating elements to define upon the translucent panel of the casing a 100 sensible indication. 105

3. In a changeable exhibitor, a casing having a translucent panel in the longitudinal wall thereof, the casing including a base, a plurality of brackets spaced longitudinally of said base and extending upwardly therefrom, said brackets being secured at their lower ends to the base and having aligned openings formed therein at points spaced vertically from the base, a bar extending through said openings and secured to each of said brackets, illuminating elements carried by said bar, and means supported from the brackets limiting passage of the rays from the illuminating elements to define upon the translucent panel of the casing a sensible indication comprising a continuous perforated curtain, each of said brackets being provided at the upper end thereof with a rotatable pulley, the pulleys being arranged in a common plane and having the outer faces thereof grooved, and a belt secured to the inner face of the upper edge of said curtain and having its inner face shaped to conform to the groove of the pulleys. 115 120 125 130

4. In a changeable exhibitor, a casing having a translucent panel in the longitudinal wall thereof, the casing including a base, a plurality of brackets spaced longitudinally of said base and extending upwardly therefrom, said brackets being secured at their lower ends to the base and having aligned openings formed therein at points spaced vertically from the base, a bar extending through said openings and secured to each of said brackets, illuminating elements carried by said bar, means supported from the brackets limiting passage of the rays from the illuminating elements to define upon the translucent panel of the casing a sensible indication comprising a continuous perforated curtain, each of said brackets being provided at the upper end thereof with a rotatable pulley, the pulleys being arranged in a common plane and having the outer faces thereof grooved, a belt secured to the inner face of the upper edge of said curtain and having its inner face shaped to conform to the groove of the pulleys, means for driving one of said pulleys, and means for adjusting another of said pulleys toward and away from the first named pulley. 25
5. In a changeable exhibitor, a plurality of supports, a plurality of pulleys carried by the supports and arranged in a common plane and having their peripheries provided with V-shaped grooves, means for driving one of said pulleys, means for adjusting another of said pulleys toward and away from the first named pulley, an endless carrier belt fitting into the grooves of all of said pulleys, a perforated skirt secured to the outer face of said carrier belt and depending therefrom, said pulleys being of greater diameter than the width of any portions of said supports arranged between the opposed portions of the skirt whereby said skirt is free from engagement with said supports. 30 25
- In testimony whereof I hereunto affix my 40 45 signature.

CHARLES ROEMER.
